UNITED STATES PATENT OFFICE.

REA P. WRIGHT, OF WASHINGTON, DISTRICT OF COLUMBIA, ASSIGNOR TO JOHN FRANCIS HEMENWAY, OF NEW YORK, N. Y.

ADJUSTABLE AUTOMATIC PRESSURE-ROLL RELEASE FOR CLOTHES-WRINGERS.

1,231,467.

Specification of Letters Patent.

Patented June 26, 1917.

Application filed October 2, 1916. Serial No. 123,381.

To all whom it may concern:

Be it known that I, REA P. WRIGHT, a citizen of the United States, residing at Washington, in the District of Columbia, have invented certain new and useful Improvements in Adjustable Automatic Pressure-Roll Releases for Clothes-Wringers, of which the following is a specification, reference being had therein to the accompanying drawing.

This invention relates to certain new and useful improvements in adjustable automatic pressure roll release for clothes wringers, the object being to provide an automatic release which is exceedingly simple and cheap in construction, and one which is composed of a very few parts so constructed that they can be readily applied to a clothes wringer of the ordinary construction so that the pressure means for the pressure rolls can be instantaneously released when the upper roll has moved a predetermined distance upwardly so that in case of a foreign object being drawn between the pressure rolls, the pressure will be released.

Another and further object of the invention is to provide an automatic pressure release in which a pair of pivoted latches are mounted on the side bars of said frame that engage the top bar and hold the same in position within the frame, the lower ends of said latches carrying adjustable trip members which are adapted to be engaged by conical-shaped members carried by the shaft of the upper pressure roll.

Other and further objects and advantages of the invention will be hereinafter set forth and the novel features thereof defined by the appended claims.

In the drawings,

Figure 1 is a side view of a clothes wringer partly in section showing the application of my improved construction of automatic release thereto;

Fig. 2 is an end view of the same;

Fig. 3 is a detail perspective view of the automatic releasing mechanism detached.

Fig. 4 is a detail view of a slightly modified form showing the cam surfaces carried by the bearing for actuating the pivoted latch.

Like numerals of reference refer to like parts in the several figures of the drawing.

In the drawing I have shown a clothes

wringer comprising a frame having slotted side bars 1 in which are mounted superposed bearings 2 and 3 carrying shafts 4 and 5 provided with wringer rolls 6 and 7 having meshing gears, not shown, inclosed by gear casings. The upper bearings 3 are provided with spring supports 8 on which are mounted pressure springs 9 engaged by bearing plates 10 carried by a pressure bar 11. The bearing plates 10 are adapted to be engaged by pressure screws 12 mounted in threaded boxes 13 carried by a movably mounted top bar 14 which is slidably mounted within the slotted upper portions of the side bars 1.

Extending into the slot of the side bar of the wringer frame are screws 15 on which are mounted the apertured ears 16 of pivoted latches 17 adapted to engage the ends of the top bar 14 and hold the same in predetermined position within the wringer frame.

The pivoted latches 17 are provided with depending tail portions 18 working in guide members 19 carried by the side bars 1 of the wringer frame, the lower ends of said tail portions being offset as shown at 20, and on which are adjustably mounted trip members 21 which are provided with slots 22 through which bolts 23 extend, carried by the tail portions, said bolts having thumb nuts 24 for clamping the trip members 21 in adjusted position thereon for the purpose hereinafter fully described.

The ends of the upper shaft 5 of the pressure roll 7 extend outwardly beyond the wringer frame and are provided with truncated cones 25 adapted to engage the trip members 21 when the pressure roll 7 moves vertically within the wringer frame so as to force the tail portions of the pivoted latches 17 inwardly which throws the latches out of contact with the movably mounted top bar so as to instantaneously release the pressure on the pressure rolls. It will be seen that by adjusting the trip members 21 on the tail portions of the latches the distance of traveling the upper pressure roll can be determined so as to cause the pressure to be released at the proper time.

In the modification shown in Fig. 4, the upper bearings 26 are provided with extensions having cam faces 27 which are adapted to engage the adjustably mounted trip

members 28 carried by the pivoted latches so as to move the latches inwardly to release the top bar.

In the operation of the automatic release as herein shown and described, as the upper roll moves vertically beyond the ordinary distance of movement in wringing clothes, the conical members carried by the ends thereof are brought into engagement with the trip members 21, and on the further upward movement the trip members ride on the conical surfaces thereof so as to cause the tail portions of the latches to be moved inwardly in order to throw the latches out of the path of travel of the top bar.

15 I claim:

1. A clothes wringer, comprising a frame having pressure rolls and pressure means for said rolls, pivoted members for normally holding said pressure means in predetermined position, and conical members carried by the shaft of one of said pressure rolls engaging said pivoted members on the upward movement thereof to release said pressure means.

2. A clothes wringer, comprising a frame having pressure rolls and pressure means for said rolls, means for normally holding said pressure means in predetermined position, said means being adjustable in respect to the pressure rolls of said wringer, and conical members carried by the shaft of one of said pressure rolls engaging said means on the upward movement thereof for releasing said pressure means.

3. A clothes wringer, comprising a frame having pressure rolls and pressure means for said rolls, movable members for normally holding said pressure means in predetermined position, adjustable trip members carried by said movable members, and conical members carried by the shaft of one of said pressure rolls engaging said adjustable members for shifting said movable members in position to release said pressure means.

4. A clothes wringer, comprising a frame having pressure rolls and pressure means for said rolls mounted therein, movable members for normally holding said pressure means in predetermined position, adjustable trip members carried by said movable members, and members having inclined faces engaging said adjustable members on the separation of said pressure rolls for moving said movable members in position to release said pressure means.

5. A clothes wringer, comprising a frame having pressure rolls and pressure means for said rolls, a top bar movably mounted within said frame having pressure screws for adjusting said pressure means, pivoted latches for holding said top bar in predetermined position within said frame, trip members adjustably mounted on said pivoted members, and conical members carried

by the shaft of one of said pressure rolls engaging said trip members for moving said pivoted members out of the path of travel of said top bar.

6. A clothes wringer, comprising a frame having pressure rolls and pressure means for said rolls mounted therein, a top bar movably mounted within said frame having means for adjusting said pressure means, pivoted members mounted upon the frame of said wringer for holding said top bar in predetermined position within said frame, said pivoted members being provided with depending tail portions, trip members adjustably mounted upon said tail portions, and conical members carried by the shaft of one of said pressure rolls engaging said trip members for oscillating said pivoted members to shift said members out of the path of travel of the top bar to release said pressure means.

7. A clothes wringer, comprising a frame having pressure rolls and pressure means for said rolls mounted therein, a top bar movably mounted within said frame having pressure screws for adjusting said pressure means, pivoted latches mounted on the side bars of said frame for holding said top bar in predetermined position within said frame, trip members adjustably carried by said pivoted latches, and conical members carried by the shaft of one of said pressure rolls engaging said trip member on the upward movement thereof for oscillating said trip member to move said trip member out of the path of travel of said top bar.

8. A clothes wringer, comprising a frame having pressure rolls and pressure means for said rolls mounted therein, a movably mounted member arranged in said frame having means for adjusting said pressure means, pivoted latches mounted on the side bars of said frame coacting with said movable member for holding said movable member in predetermined position within said frame, said latches having depending offset tail portions carrying bolts, slotted trip members adjustably mounted on the bolts of said tail portions, and conical-shaped members mounted on the shaft of one of said pressure rolls engaging said trip members on the separation of said rolls for moving said pivoted latches out of the path of travel of said movable mounted member.

9. A clothes wringer, comprising a frame having pressure rolls and pressure means for said rolls, movably mounted members for holding said pressure means in predetermined position, and members having inclined faces operated by the vertical movement of one of said pressure rolls engaging said movable member for moving said movable members in position to release said pressure means.

10. A clothes wringer, comprising a frame having pressure rolls and pressure means for said rolls mounted therein, means for normally holding said pressure means in predetermined position, said means being adjustable in respect to the pressure rolls of said wringer, and means actuated by the vertical movement of one of said rolls for shifting said means in position to release said pressure means.

11. A clothes wringer, comprising a frame having pressure rolls and pressure means for said rolls mounted therein, pivoted members for normally holding said pressure means in predetermined position, trip members carried by said pivoted members, and members having inclined faces engaging said trip members on the vertical movement of one of said pressure rolls for shifting said pivoted members in position to release said pressure means.

12. A clothes wringer, comprising a frame having pressure rolls and pressure means for said rolls mounted therein, a movably mounted top bar having means for adjusting said pressure means, pivoted members for holding said top bar in predetermined position within said frame, trip members carried by said pivoted members, and members actuated by the separation of said pressure rolls having inclined faces engaging said trip members for moving said pivoted members out of the path of travel of said top bar for releasing said pressure means.

mined position within said frame, trip members carried by said pivoted members, and members actuated by the separation of said pressure rolls having inclined faces engaging said trip members for moving said pivoted members out of the path of travel of said top bar for releasing said pressure means.

13. A clothes wringer embodying a tension controlled roll, springs confined against the ends thereof, a pressure member, a shiftable element mounted upon the wringer frame and operating to lock the pressure member to maintain the springs under tension, and means for automatically shifting said elements to unlock said member to release the tension of the springs upon the roll, the said element and roll being provided one with an inclined face and the other with a projection, one movable over the other for shifting said element, one of said elements having an adjustable contacting member for timing the release of the pressure means.

In testimony whereof I hereunto affix my signature.

REA P. WRIGHT.
